[57] CLAIM

The ornamental design for a pitot tube cover, as shown and described.

DESCRIPTION

FIG. 1 is a front, top and right side perspective view of a pitot tube cover of a first embodiment;

FIG. 2 is a front elevation view thereof, rotated 90 degrees;

FIG. 3 is a rear elevation view thereof;

FIG. 4 is a top plan view thereof, the bottom view being a mirror image except as indicated by FIG. 5;

FIG. 5 is a cross-sectional view taken along line 5—5 of FIG. 4; and,

FIG. 6 is a top plan view of a pitot tube cover of a second embodiment of this invention. With the exception of the exact configuration of the spring wire and the length of the front tube, the bottom view is a mirror image while the rear and cross-sectional views are identical to that shown in FIGS. 3 and 5.
